COMBUSTION APPARATUS FOR FURNACES

William Ferguson, Philadelphia, Pa., assignor to
National Airoil Burner Company, Incorporated,
Philadelphia, Pa., a corporation of Delaware

Application December 1, 1947, Serial No. 789,101

7 Claims. (Cl. 158—1)

1

This invention relates to furnaces, and more particularly to improvements in furnaces and burners therefor.

It has heretofore been proposed to provide center and single wall up-draft heaters, particularly for use in petroleum refinery processes, and in other heating processes where a substantial portion of the fuel heat is to be absorbed from flame radiation.

These furnaces have heretofore been fired by gas burners directed upwardly. The gas burners were not, however, readily removable for inspection and repair while the furnace was in operation.

No satisfactory provision has heretofore been made for the use of oil fuel firing heaters of this type.

It is desirable, in modern refinery practice, that provisions be made in the furnace to satisfactorily burn liquid or gaseous fuel, as desired.

It is the principal object, therefore, of the present invention to provide a furnace and burners therefor which are suitable for the combustion of gaseous fuel or oil, as desired.

It is a further object of the present invention to provide an improved furnace and burner construction for burning gaseous fuel or oil and in which substantially the same flame pattern may be provided with either type of fuel.

It is a further object of the present invention to provide an improved furnace and burner construction with provisions for burning gaseous fuel or oil, as desired, and in which operation with either of the fuels may be effected, as desired, without damage or injury to either burner.

It is a further object of the present invention to provide an improved furnace and burner construction in which a plurality of burners are provided for combustion of oil and gaseous fuel in which the burners are arranged in series to insure a better character of combustion, as well as stable ignition over a wide range of capacity.

It is a further object of the present invention to provide an improved furnace and burner construction with provisions for pairs of burners, one of each pair for oil and one of each pair for gas fuel, and in which either burner of the pair may be withdrawn for inspection and repair while the other burner is in operation.

It is a further object of the present invention to provide an improved furnace and burner construction with provisions for burning gaseous fuel and oil, as desired, and in which the gas burner housing is protected against overheating.

It is a further object of the present invention to provide an improved furnace and burner construction in which a plurality of refractory throats are provided in series for accommodating burners for oil and gas fuel and in which the

2

areas of the throats correspond with the optimum flame cross-section.

Other objects and advantageous features of the invention will be apparent from the specification.

The nature and characteristic features of the invention will be more readily understood from the following description, taken in connection with the accompanying drawings forming part hereof, in which:

Fig. 1 is a vertical sectional view through a furnace in accordance with the present invention, and illustrating the construction and arrangement of the burners for oil and for gaseous fuel;

Fig. 2 is a sectional view taken approximately on the line 2—2 of Fig. 1;

Fig. 3 is a plan view of one of the burner elements employed in connection with the present invention;

Fig. 4 is a top plan view, enlarged, of a portion of another of the burner elements employed in connection with the present invention;

Fig. 5 is a front view, partly in elevation and partly in vertical section, of the burner element shown in Fig. 4; and

Fig. 6 is a vertical sectional view taken approximately on the line 6—6 of Fig. 5.

It should, of course, be understood that the description and drawings herein are illustrative merely, and that various modifications and changes may be made in the structure disclosed without departing from the spirit of the invention.

Similar numerals refer to similar parts throughout the several views.

Referring now more particularly to the drawings, in which a preferred embodiment of the invention is illustrated, a furnace is shown in part which includes a vertical front wall 10, and a vertical wall 11 parallel to the front wall 10. The wall 11 may be the side or rear wall or the center wall of an updraft heater or furnace of conventional type. One of the vertical end walls is illustrated at 12. The walls 10, 11 and 12 are of suitable refractory material. The lowermost tube of a series of tubes to be heated is shown at 9.

The furnace is supported upon a foundation or horizontal floor 13 and spaced upwardly therefrom horizontal walls 14 and 15 are provided. In the space between the floor 13 and the wall 14, and extending forwardly from the wall 11 a plurality of spaced vertical walls 16 are provided, the passageways therebetween constituting lower air ducts 17, for purposes to be explained.

Similarly, in the space between the wall 14 and the wall 15, and extending forwardly from the wall 11, a plurality of spaced vertical walls 18 are provided, the passageways therebetween constituting upper air ducts 19, for purposes to be ex-

plained. Spaced forwardly from the front wall 10, a front wall plate 20 is provided in which adjustable lower air doors 21 are carried for regulating the supply of air to the lower air ducts 17 and adjustable upper air doors 22 are carried for regulating the supply of air to the upper air ducts 19.

The furnace is provided, in accordance with its size, with a plurality of pairs of upper and lower air ducts 19 and 17 between the end walls thereof, although for purposes of explanation only two pairs of ducts have been illustrated.

The horizontal wall 14 is provided at the wall 11 with lower burner blocks 25 of refractory material, supported by the wall 14 and the wall 11, one burner block 25 being employed for each air duct 17. Each of the burner blocks 25 has a central opening or throat 26. The openings or throats 26, as illustrated in Fig. 1, are inclined from the vertical, preferably at an angle of the order of 10 degrees with respect to the wall 11 and are flaring, as illustrated in Fig. 2, from the lower to the upper ends thereof to provide a flaring flame pattern.

Upper burner blocks 27 are also provided of refractory material, in the wall 15 at the wall 11 and are supported by the walls 11, 15 and 18, one block 27 being provided for each air duct 19. Each of the upper burner blocks 27 also has a central opening or throat 28 at the same inclination as the opening 26 and aligned therewith, and flaring, as indicated in Fig. 2, with the side margins of the openings or throats 28 substantially in alignment with the corresponding margins of the openings or throats 26 of the lower burner blocks 25.

An oil burner element 30 is provided for each of the lower ducts 17 and is removably mounted therein. Each of the oil burner elements includes an oil supply pipe 31, connected to any suitable supply of oil to be fired and to a manifold 32, a control valve 33 being provided in the supply pipe 31 for controlling the quantity of oil supplied.

A fluid connection 34 is provided, connected to a suitable source of atomizing fluid such as steam or air under pressure and to the manifold 32. A control valve 35 is provided in the fluid connection 34 for controlling the quantity of atomizing fluid. The manifold 32 has a bypass valve 36 therein. The manifold has an oil delivery pipe 37 and an atomizing fluid delivery pipe 38 connected thereto, the other terminal ends of the pipes 37 and 38 being connected by swivel joints to an atomizing nozzle 40.

The pipes 37 and 38 are preferably secured to suitable supports 41 and 42 which are slidable in channels 43 in each of the ducts 17. The support 42 is preferably provided with an upwardly extending plate 44 in which is carried a threaded adjusting rod 45. The rod 45 has a collar 46 in engagement with the nozzle 40 and nuts 47 on the rod 45 permit of adjustment of the inclination of the nozzle 40.

The nozzle 40 is preferably adjusted to the desired angle of inclination and in conformity with the inclination of the openings or throats 26 and 28 in the lower and upper burner blocks 25 and 27 and is centered with respect thereto.

A front cover plate 50 is provided, preferably removably mounted on the front wall plate 20 for permitting the withdrawal of the burner element 30 as desired and as hereinafter explained.

A gas burner element 55 is provided for each of the upper air ducts 19. The burner element 55 is preferably an inspirating gas burner of the

conventional Venturi type and in which from 40 to 100 percent of the total air for combustion of the gas, depending on the gas pressure, is drawn into the Venturi section 56.

5 A gas supply pipe 57 is provided, connected to the Venturi section 56 at one end, an air inlet adjusting plate 58 being mounted on the Venturi section 56. The plate 58 is adapted to be positioned to determine the quantity of air admitted 10 to the Venturi section 56 by a threaded rod 59 carried in a plate 60 mounted on the pipe 57 outside the wall plate 20 and rotated by a handle 61. A handle 62 is also mounted on the pipe 57 for positioning the burner element 55 in the duct 19.

15 The Venturi section 56 has connected to the other end a pipe nipple 65, of a length in accordance with the particular furnace, and on the outer end of the nipple 65 a manifold burner casing 66 is mounted and supported. The manifold burner casing 66 is provided with an upper wall 67 in which a plurality of main circular ports or orifices 68 are provided, the orifices 68 preferably being aligned in one plane and also being disposed at an inclination to provide an approximately flat sheet of flame. Adjacent the ports or orifices 68 a plurality of smaller ports 69 are provided to emit and direct sufficient of the gas-air mixture at a lower velocity against the gas discharged through the openings 68 for insuring ignition.

30 The exterior of the casing 66 and particularly the top wall 67 thereof is preferably provided with a coating of refractory heat insulating plastic material 63, in suitable recesses in the upper face of the top wall 67, to prevent overheating of the casing 66. The casing 66 is also provided with a vertical wall 64 having a boss 70 for the reception of a mounting stud 71 in engagement with a boss 72 on a vertically disposed manifold burner shield 73. The exposed surface of the shield 73 is recessed and is provided with refractory insulating material 74 for screening the manifold casing 66 from excessive heat radiation, as hereinafter explained.

35 40 45 The burner element 55 is supported by spaced supports 75 in engagement therewith, which are adapted to slide upon a channel 76 on the lower wall of the duct 19. The burner element 55 is adapted to be positioned by movement thereof by the handle 62 to a position with the openings 68 in alignment with and centrally at the throat 28, or withdrawn to a position indicated in broken lines in Fig. 1, in which the burner casing 66 is protected by the shield 73 which substantially closes the duct 19.

50 The mode of operation will now be pointed out. When it is desired to supply heat to the furnace and particularly for heating the wall 11 for emitting radiant heat either of the burner units

94

the throat 26 to the throat 28 and in so doing aids in cooling the casing 66 which is protected from the heating effect of the radiant heat by the shield 73. If at any time it is desired to purge the oil in the pipe 37 this may be done by closing the valve 33 and opening the valve 36 to pass the atomizing fluid through the pipe 37.

If, on the other hand, it is desired to heat the furnace with gas fuel, the burner unit 55 is positioned as indicated in Fig. 1 with the openings 68 at the proper positions with respect to the throat 28. Gas supplied from the pipe 51 is delivered to the Venturi section 5 where air is inspirated in accordance with the positioning of the plate 58 and mixed with the gas for delivery through the nipple 65 to the casing 66. The flame from the gas-air mixture discharged through the openings 68, passes upwardly through the throat 28. Air is admitted through the duct 19 in accordance with the positioning of the door 22 for supplying the additional air as required for combustion of the gas-air mixture.

If desired, also, air may be admitted through the duct 17, as determined by the positioning of the door 21, for additional cooling of the casing 66 and for aiding in the completion of combustion of the gas-air mixture.

It will be noted that either of the burner elements 30 or 55 may be employed, as desired, without damage by heat to the burner element which is not in use. At the same time adequate provision is made for the introduction of air for combustion, which air may also be utilized for cooling the casing 66 of the burner element 55. At the same time the flame pattern from either of the burners is accommodated and directed at the desired inclination.

I claim:

1. In a furnace, spaced walls at the lower portion of the furnace providing a plurality of horizontally disposed air ducts in vertical pairs, members for controlling the delivery of air into each of said ducts, burner blocks at the inner ends of said ducts having throat portions in alinement, a fuel burner mounted in one of said ducts of each pair and having a discharge portion for alinement with one of said throat portions, the other of the ducts of each pair being adapted to receive another fuel burner, and said other fuel burner having a discharge portion for alinement with the other of said throat portions.

2. In a furnace, spaced walls at the lower portion of the furnace providing a plurality of air ducts in pairs, members for controlling the delivery of air into each of said ducts, burner blocks at the inner ends of said ducts having throat portions in alinement, a fuel burner retractably mounted in one of the ducts of a pair and having a discharge portion for alinement with one of said throat portions, the other of said air ducts of each pair being adapted to receive another retractable fuel burner, and said other fuel burner having a discharge portion for alinement with the other of said throat portions.

3. In a furnace, spaced walls at the lower portion of said furnace providing a plurality of horizontally disposed air ducts in vertical pairs, members for controlling the delivery of air into each of said ducts, vertically spaced burner blocks at the inner ends of each of said ducts, said burner blocks of each pair having throat portions in alinement and at an inclination with respect to the vertical, a burner in one of the ducts of each pair having a discharge portion for alinement with one of said throat portions, the other of said

ducts of each pair being adapted to receive another fuel burner, and said other fuel burner having a discharge portion for alinement with the other of said throat portions.

5. In a furnace, spaced walls at the lower portion of the furnace providing a plurality of horizontally disposed air ducts in vertical pairs, members for controlling the delivery of air into each of said ducts, a burner in the lower of the ducts of each pair, and means for controlling the flame pattern from said burner including burner blocks for each of said air ducts vertically spaced in each pair, the upper of said air ducts being adapted to receive another fuel burner, said other fuel burner having a discharge portion for alinement with said throat portions.

10. In a furnace, spaced walls at the lower portion of the furnace providing a plurality of horizontally disposed air ducts in vertical pairs, members for controlling the delivery of air into each of said ducts, a fuel burner retractably mounted in one of said ducts of each pair, the other of the air ducts being adapted to receive another fuel burner, and means for controlling the flame pattern from said burners including vertically spaced burner blocks for each of said air ducts having spaced throats, said throats having substantially alined flaring marginal walls.

15. In a furnace, spaced walls at the lower portion of the furnace providing a plurality of horizontally disposed air ducts in vertical pairs, members for controlling the delivery of air into said ducts, a fuel burner retractably mounted in one of said ducts of each pair, the other of said ducts of each pair being adapted to receive another fuel burner, and means for controlling the flame pattern from said burners including spaced burner blocks for each of said air ducts, said burner blocks having throats in alinement and at an inclination with respect to the vertical and with substantially alined flaring marginal walls.

20. In a furnace, spaced walls at the lower portion of the furnace providing a plurality of horizontally disposed air ducts in vertical pairs, members for controlling the delivery of air into each of said ducts, burner blocks at the inner ends of said ducts having throat portions in alinement, a burner retractably mounted in one of said ducts of each pair and having a discharge portion for alinement with one of said throat portions, the other of the ducts of each pair being adapted to receive another retractable fuel burner, said other fuel burner having a discharge portion for alinement with another of said throat portions, and 25 one of said fuel burners having a shielded end portion for substantially closing the duct in which it is disposed in retracted position.

WILLIAM FERGUSON.
